UNITED STATES PATENT OFFICE.

HARRY L. FRENCH, OF PORT HURON, MICHIGAN.

DEVICE FOR TYING PACKAGES.

No. 893,234.

Specification of Letters Patent.

Patented July 14, 1908.

Application filed December 28, 1907. Serial No. 408,438.

To all whom it may concern:

Be it known that I, HARRY L. FRENCH, a citizen of the United States, residing at Port Huron, in the county of St. Clair and State of Michigan, have invented a new and useful Device for Tying Packages, of which the following is a specification.

This invention relates to package ties.

The object of the invention is to provide an article of this character which may easily and rapidly be manipulated to effect stable assemblage of mail matter, and in which the binder or cord used will be positively prevented from loosening or becoming detached from the package with which it is assembled, thereby to insure the proper delivery of such packages. Furthermore, to facilitate the assemblage of the binder with the locking or fastening element, thus to save time in case of breakage of the binder.

With the above and other objects in view, as will appear as the nature of the invention is better understood, the same consists in the novel construction and combination of 25 parts, of a package tier, as will be hereinafter fully described and claimed.

In the accompanying drawings forming a part of this specification, and in which like characters of reference indicate corresponding parts, Figure 1 is a view in perspective of the binder locking member of the tier, the binder being omitted. Fig. 2 is a perspective view displaying the manner in which the article is used in holding assembled a pack- 35 age of mail matter. Fig. 3 is a view in side elevation of the device, the binder being omitted.

The binder locking member, shown in Fig. 1, is constructed from a length of resilient 40 wire, that is preferably flattened on two parallel sides, and is bent to form a thumb rest 1 that is approximately ovate in shape and is then double rebent to form a binder receiving throat 2, the terminals of the wire 45 being formed into eyes 3 that project beyond the entrance of the throat 2 and are disposed approximately parallel with the thumb rest.

The members of the locking device under the thumb rest are arranged in approximate 50 parallelism to provide a binder locking crotch 4, as clearly shown in Fig. 2, the noses 5 formed by rebending the stock being projected slightly into the opening of the thumb rest in order to prevent the binder from en-

tering at that point. The binder 6, which 55 may be a length of cord of any preferred character, has one end secured in the eyes 3 and is to be of sufficient length to pass any desired number of times around the package or mail matter M both longitudinally and 60 transversely thereof.

In the use of the article, the locking member is placed upon the package of mail matter with the eye portion resting thereon, and with the thumb of the operator bearing upon 65 the thumb rest and his fingers grasping the package of mail. The binder is then passed lengthwise around the letters, or the like, one or more times, in the direction of the arrow x shown in Fig. 2, then passed through 70 the throat 2 and turned one or more times around the package in the direction of the arrow y, then turned one or more times around the noses 5, and is finally pinched into the locking crotch 4, where it is posi- 75 tively held against yielding or slippage.

While the device is herein described for use in assembling mail matter, it is to be understood that it is equally adaptable for securing the mouths of different kinds of 80 sacks and, as this will be readily understood, detailed illustration thereof is omitted.

I claim:

1. A package tier comprising a length of wire bent to form a thumb rest and then 85 double rebent in opposite directions to form a binder receiving throat, the portion of the wire forming the throat being projected into the thumb rest and forming a binder locking crotch, and the terminals of the wire being 90 formed into eyes.

2. A package tier comprising a length of wire bent to form a thumb rest and then double rebent in opposite directions to form a binder receiving throat, the portion of the 95 wire forming the throat being projected into the thumb rest and forming a binder locking crotch and the terminals of the wire being formed into eyes, and a binder having one end secured in the eyes. 100

In testimony that I claim the foregoing as my own, I have hereto affixed my signature in the presence of two witnesses.

HARRY L. FRENCH.
